Application filed December 15, 1931. Serial No. 42,089. Term of patent 7 years.

To all whom it may concern:

Be it known that I, GEORGE AINSWORTH, a citizen of the United States, residing at New Hyde Park, in the county of Nassau and State of New York, have invented a new, original, and ornamental Design for a Lighting Fixture, of which the following is a specification, reference being had to the accompanying drawing, forming part thereof, in which—

The figure is a side elevation of a lighting fixture embodying my ornamental design.

My design comprises a bowl of the shape shown in the drawings but in order to produce an artistic and beautiful effect when illuminated it must be made of a very dense translucent glass having a fire polished interior.

I claim:

The ornamental design for a lighting fixture substantially as shown and described.
